(57) **CLAIM**

The ornamental design for a display screen with graphical user interface, as shown and described.

DESCRIPTION

1. Display Screen with Graphical User Interface
1.0 is a front view of a display screen with graphical user interface showing the new design.

(Continued)

The broken line showing in the figure depicts portions of the display screen with graphical user interface that forms no part of the claimed design.

1 Claim, 1 Drawing Sheet
